(Cl. D34—15)

FIG. 1

FIG. 4

FIG. 1 is a side elevational view of the cradle showing my new design;

FIG. 2 is an end elevational view of the cradle shown in FIG. 1, taken from the right hand side of FIG. 1;

FIG. 3 is a top plan view of the cradle; and

FIG. 4 is an end elevational view of the cradle taken from the left hand side of FIG. 1.

The broken line showing of a doll and pillow in FIG. 3 is for purposes of illustration only. The bottom of the cradle is flat and unornamented.

I claim:

The ornamental design for a toy cradle, as shown and described.
